UNITED STATES PATENT OFFICE

HERBERT R. SAGE, OF LOS ANGELES, CALIFORNIA

HOT CAP

Application filed May 4, 1931. Serial No. 534,855.

In this specification, and the accompanying drawings, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

This invention relates to the construction of so-called "hot-caps" for protecting seeds and young plants, to hasten and otherwise aid their growth. The salient objects of the invention include; first, to provide an improved form of hot-cap for the above purpose, and an economical method for producing it; second, to provide a hot-cap construction that is better adapted to withstand the effects of wind and rain, than the devices that have hitherto been produced for this purpose; third, to provide a device of this character that will strongly resist collapsing by reason of the weight of any moisture or frost that may collect thereupon; fourth, to furnish a hot-cap that is adapted for selectively filtering solar radiation to eliminate such rays as are considered to be harmful to young plant growth; and fifth, to secure the foregoing objects in a device that also tends to repel destructive insects. Other objects and advantages of the invention will appear in the subjoined detailed description.

My objects are attained in the manner illustrated in the accompanying drawings which show an approved form of the invention, and in which:—

Figure 1 is a fragmentary plan view of a sheet of prepared material from which the blanks for forming the caps are to be cut, showing a preferred arrangement of such blanks with respect to the material;

Figure 2 is a plan view of a cap blank after being cut from the material, and after being otherwise prepared for being formed into a completed cap;

Figure 3 is a partly broken elevation of a completed cap, showing the manner in which it may be anchored in place in the earth; and,

Figure 4 is a plan view of a completed cap. Figures 1 and 2 are drawn to the same scale; and Figures 3 and 4 are drawn to a somewhat larger scale. Similar reference numerals refer to similar parts throughout the several views.

In manufacturing my hot-caps I first take a long strip of suitable material, such as properly prepared water-proofed paper in roll form, and attach a series of longitudinal spaced reinforcing strips to one side thereof, as by means of paraffine wax or other water-proof adhesive. This may be accomplished by a continuous process in ways that are well understood. A sheet of such material is shown at 5, and the reinforcing strips are shown at 6.

The cap blanks, in the form of circular sectors or annular sectors, are cut from the thus prepared sheet. The form of my invention that has been selected for illustration is a hollow truncated cone, and the blanks from which such caps are made are annular sectors cut from the prepared sheet along the dotted lines 7, 8, and 9. I prefer to cut the blanks from the prepared sheet in such a manner that the reinforcing strips will be perpendicular to the axes of symmetry of the blanks, as illustrated.

After being severed from the prepared sheet, radial kerfs 10 are cut inwardly a uniform distance from the larger circular portion of the perimeter of the blanks, and they will then appear as shown in Fig. 2.

The blanks are next formed into a conical cap over a mandrel, with the reinforcing strips on the inside, and with edges 11 and 12 overlapped by the amount indicated by broken line 13. These overlapped portions are then joined together by means of a water-proof adhesive.

Finally the flaps 14 are bent outwardly to form what amounts to a kerfed circular flange at the base of the conical cap as shown in Fig. 4. These flaps may have earth placed over them, in the manner illustrated at 15 in Fig. 3, and thus are adapted to serve as means for anchoring the caps in place.

The shaping of the cap blanks into cones will cause reinforcing strips 6 to assume the

form of loops, in planes that intersect the axis of the cone obliquely. These reinforcing loops are either closed on themselves or terminate at the supported base of the cone, and 5 are thus adapted to act as structural arches for resisting lateral pressure against the cap. The fact that the planes of these loops are oblique to the axis of the cone, enables the reinforcing strips to act structurally as diagonal braces also, to resist vertical forces that 10 might otherwise cause the cap to collapse, such as the weight of accumulated water or frost upon the outer surface.

I prefer to use for the material of the caps, 15 a suitable kind of waterproofed paper, such as paraffined paper, of a quality and color that is adapted to act as a selective filter of solar radiation to exclude such rays as may be considered harmful to young plant life. 20 In this manner both the opacity and color of the material may be selected to produce the maximum beneficial effect. The material may be impregnated or otherwise treated with substances such as creosote or arsenical 25 compounds, to repel the invasion of destructive insects, and thus add to the usefulness of the device.

I also prefer to make my cap in the form 30 of a truncated cone, as illustrated, for several reasons. This form provides a small circular opening 16 at the top of the cap, that is necessary for ventilating purposes. The growing plant will, in time, extend through this 35 opening; and further growth of the plant, after it has reached this stage and no longer requires the protection of the cap, will finally result in tearing the relatively weak material of which the cap is formed. Thus the caps eventually will be automatically removed by 40 the growth of the plant that was protected thereby in its early life. In this truncated form of cap therefore, there will be no necessity for hand removal.

It will be obvious that the arrangement 45 of the cap blanks with reference to the prepared material from which they are cut, may be considerably varied, and it also will be plain that various departures may be made in the arrangement, spacing, and dimensions, 50 of reinforcing strips 6. Such departures will result in a more or less different arrangement of the reinforcement of the completed cap; but, in any event, the reinforcing strips will 55 tend to take the form of structural arches, disposed in planes that are oblique to the axis of the cap.

The drawings, for purposes of clarity, show 60 the material of the cap, and of the reinforcing strips, as being of considerable thickness. In practice these are much thinner in proportion 65 than the illustrations indicate. Nevertheless the reinforcing strips will add very materially to the mechanical strength of the cap to resist collapse by reason of superposed

moisture or frost, and to resist the lateral force of wind pressure.

Having thus fully described my invention, I claim:

1. A hot-cap comprising, a hollow conical body with spaced encircling reinforcing strips on its surface; said strips being substantially in planes that intersect the axis of the body obliquely. 76

2. A hot-cap comprising; a hollow conical body with spaced encircling reinforcing strips on its interior surface; said strips being substantially in parallel planes that intersect the axis of the body obliquely. 75

3. A hot-cap comprising, a hollow conical body with spaced encircling reinforcing strips on its interior surface; said strips forming closed loops and being substantially in planes that intersect the axis of the body obliquely. 80
